(57) **CLAIM**

The ornamental design for a portion of a label for a bottle, as shown and described.

DESCRIPTION

FIG. 1 is a front view of a portion of a label for a bottle; FIG. 2 is a top perspective view thereof; and,

FIG. 3 is a top perspective view of a portion of a label showing another embodiment of our new design.

The uneven broken line showing of the remainder of the label and the bottle is for illustrative purposes only and forms no part of the claimed design.

1 Claim, 3 Drawing Sheets

FIG. 1

FIG. 2

FIG. 3
